UNITED STATES PATENT OFFICE.

DANIEL BENTON WOOD, OF ALMYRA, ARKANSAS, ASSIGNOR TO WOOD AIRMOTER CO., OF ALMYRA, ARKANSAS.

AIR-MOTOR.

No. 910,342.

Specification of Letters Patent.

Patented Jan. 19, 1909.

Application filed January 15, 1908. Serial No. 410,955.

To all whom it may concern:

Be it known that I, DANIEL BENTON WOOD, a citizen of the United States, residing at Almyra, in the county of Arkansas and State 5 of Arkansas, have invented certain new and useful Improvements in Air-Motors, of which the following is a specification, reference being had to the accompanying drawings.

My invention relates to improvements in 10 windwheels of that type which are horizontally disposed and provided with feathering blades.

The principal object of the invention is to 15 improve and simplify the construction and operation of windwheels or motors of this character and thereby render the same stronger, more durable and efficient and less expensive.

Another object of the invention is to provide a simple and practical mechanism for 20 feathering the blades, which mechanism will be automatically controlled.

A further object of the invention is to provide an improved means for controlling the 25 speed of the wheel either automatically or manually.

With the above and other objects in view, the invention consists of the novel features of construction and the combination and arrangement of parts hereinabove fully described and claimed, and illustrated in the 30 accompanying drawings, in which—

Figure 1 is a view partly in elevation and partly in vertical section through my improved windwheel or wind motor; Fig. 2 is a similar view taken in a plane at right angles; Fig. 3 is a horizontal section taken on the plane indicated by the line 3—3 in Fig. 1; and Figs. 4, 5 and 6 are detail views showing 40 the construction of several of the parts.

My improved windwheel comprises a vertical shaft 1 mounted for rotation in a tubular bearing sleeve or head 2, preferably of cylindrical form, arranged at the top of a tower 45 3 or any other suitable supporting structure. The embodiment of my invention illustrated has its wheel composed of upper and lower sets of feathering blades 4, but a greater or less number of sets may be employed, in the 50 former case the blades of each set are superposed in vertical alinement as illustrated. Any number of the blades 4 may be provided in each set, and each one is rotatably mount-

ed upon a spoke or arm 5 which radiates from a hub 6 in the form of a collar fixed upon the 55 shaft 1. Suitable brace rods 7 may be provided for supporting the outer ends of the spokes and reinforcing the wheel.

Each of the blades 4 has a flat body portion or plate tapered from its outer to its 60 inner end and reinforced by transverse straps 8, the central portions of which latter are bent to provide bearing collars 9 which engage and rotate upon one of the spokes 5. The superposed blades of the two series are 65 connected together for simultaneous movement by links 10 which have their ends pivoted adjacent to the central portions of the outer or upper edges of said superposed blades as clearly shown in Fig. 1. For the 70 purpose of preventing the blades from passing beyond the horizontal when they are shifted from their vertical to their horizontal positions shown in Fig. 1, I provide stops 11 in the form of U-shaped brackets which project horizontally from the spokes 5 as more 75 clearly shown in Fig. 3.

The shaft 1 may be journaled for rotation in any suitable bearing but as illustrated it projects through reduced bearing portions 12 80 at the ends of the cylinder 2; and an annular series of bearing balls 13 is arranged in opposing grooves or raceways formed in the bottom of the lower hub or collar 6 and in the top of a ring or plate 14 arranged upon 85 the upper bearing portion 12 of the cylinder 2. The lower end of the shaft 1 may be reduced and one or more suitable bearings 15 may be provided for it in the supporting structure 3.

For the purpose of feathering the blades of the wheel I preferably provide upon each one of one of the series, preferably the lower series, an inwardly projecting extension or arm 16 carrying an anti-friction roller 17 adapted 95 to run upon a cam track 18. The latter is of substantially annular form and consists of a relatively stationary section 19 and a drop section 20. Each of said track sections is of substantially semi-circular shape and they 100 have their ends pivotally or hingedly connected as shown at 21. The stationary section 19 is horizontally disposed and rigidly connected by bracket arms 22 to a rotatable collar or sleeve 23 arranged upon a reduced 105 portion 24 of the cylinder 2. The drop sec-

2
tion 20 of the track is adapted to move or swing vertically from the horizontal plane of the stationary section 19 to an angular position so as to form inclined portions which 5 lower and raise the anti-friction rollers 17 and consequently the blades 4. It will be seen that when the rollers 17 are engaged with the stationary horizontal portion or section 19 of the track the blades 4 will be 10 held in horizontal planes out of the wind, and that when said rollers move downwardly upon the drop section 20 of the track the blades will drop to their vertical position into the wind, in which latter position they will 15 remain until said rollers travel up the opposite end of the drop section 20 and on to the stationary horizontal section 19. Since the blades of the two series are connected for simultaneous movement by the links 10, the 20 blades of the upper series will swing with those of the lower one. The arms or projections 16 serve to overbalance the blades so that they will drop to their vertical position, but said blades may be overbalanced in 25 any other suitable manner.

For the purpose of changing the position of the cam track 18 as the direction of the wind changes, I provide a vane 25 arranged upon an arm 26 which is secured to one of 30 the bracket arms 22 of the rotary collar 23 that carries the track. It will be seen that this vane will shift the track as the wind changes so that the blades on one side of wheel will be turned full to the wind while 35 those upon the other side will be feathered or turned edgewise to the arm.

The drop section 20 of the track may be raised and lowered for the purpose of turning the blades to a greater or less extent to 40 the wind and thus controlling the speed of the wheel, either manually or automatically. It is controlled automatically by a vane 27 secured on the outer end of an arm or lever 28 attached to a segmental gear 29 journaled 45 on a vertical pin 30 upon one of the bracket arms 22 and adapted to mesh with a similar gear 31 journaled upon a horizontal pin or stud 32 on the rotary collar 23. The gear 31 is attached to a lever 33 having a curved 50 inner portion and a radially projecting outer end 34 adapted to extend under the center of the drop section of the track for the purpose of raising and lowering the same.

The vane 27 is much smaller than the 55 track controlling vane 25 and it is angularly arranged as more clearly shown in Fig. 3 so that it is only actuated by a strong wind. When it is moved inwardly and rearwardly, that is, in the direction of the vane 25 the 60 gears or gear segments 29, 31 will be actuated and the arm 34 will lift the drop track section 20 so that the blades will be turned to the wind to a less extent. In case of a very strong wind the arm 34 will lift the track 65 section 20 to a horizontal position so that all

of the blades will be thrown horizontal or edgewise to the wind. From the foregoing it will be seen that these parts provide a very effective speed governor for the wheel, and one which is entirely automatic in its 70 operation.

For the purpose of manually operating the drop track section 20 I provide a lever 35 in the form of a yoke which extends approximately half way around the cylinder 2 and 75 has its arms pivoted upon pins 36 which project from said cylinder. The inner ends of the arms or branches of this yoke lever are formed with cams 37 which bear, at diametrically opposite points, upon the bottom of a collar or sleeve 39 which surrounds the cylinder 2 and is vertically movable thereon. This collar 39 is guided in its vertical sliding movement by the pins 36 which project through vertical slots formed in said 80 collar. Pivoted upon the inner portion of the arm 34 is a dog 38 adapted to have its lower end bear upon the upper portion of the collar 39 so that when the latter is raised by the cams 37 the arm 34 will be raised to 85 elevate the drop section 20 of the track. A spring 39^a is provided for the purpose of pressing the dog or pawl 38 inwardly and maintaining it in engagement with the collar 39 as the arm 34 swings upwardly. The 90 other end of the lever 35 may be connected to a cord or other operating element, 40, the lower end of which may be manually operated.

From the foregoing description taken in 100 connection with the accompanying drawings it is thought that the construction, operation and advantages of the invention will be readily understood without a more extended explanation.

While I have shown and described in detail the preferred embodiment of the invention it will be understood that I do not wish to be limited to the precise construction set forth and that various changes in the 110 form, proportion and minor details may be resorted to without departing from the spirit or sacrificing any of the advantages of the invention.

Having thus described my invention what 115 I claim is:

1. In a windwheel, the combination of a vertical shaft, spokes radiating therefrom, feathering blades upon said spokes, a tubular bearing surrounding the shaft, a rotatable 120 collar upon said bearing, a track having a fixed section supported from said rotatable collar, a vertically swinging section for the track pivoted at its ends to the ends of the stationary section, means carried by the 125 blades for engagement with said track, a vane carried by said rotatable collar for holding the blades to the wind, a vertically swinging arm for raising and lowering the 130 swinging section of the track, said arm hav-

- ing its free outer end bearing upon the under face of the outer portion of said movable track section and its inner end curved and pivoted to one side of said collar, a beveled 5 pinion carried by the pivoted inner end of said arm, a second beveled pinion in mesh with the first mentioned one, a governing vane carried by the second pinion and means for manually operating said arm.
- 10 2. In a windwheel, the combination of a vertical shaft, spokes radiating therefrom, feathering blades upon said spokes, a tubular bearing surrounding the shaft, a rotatable collar upon said bearing, a track having a 15 fixed section supported from said rotatable collar, a vertically swinging section for the track pivoted at its ends to the ends of the stationary section, means carried by the blades for engagement with said track, a 20 vane carried by said rotatable collar for holding the blades to the wind, a vertically swinging arm for raising and lowering the swinging section of the track, said arm having its free outer end bearing upon the under 25 face of the outer portion of said movable track section and its inner end curved and pivoted to one side of said collar, a beveled pinion carried by the pivoted inner end of said arm, a second beveled pinion in mesh 30 with the first mentioned one, a governing vane carried by the second pinion, a ring surrounding said bearing and vertically movable thereon, a pivotally mounted spring pressed dog carried by said arm and engaged 35 with said ring and a cam lever for actuating said ring.
3. In a windwheel, the combination of a vertical shaft, spokes radiating therefrom, feathering blades upon said spokes, a tubular bearing surrounding the shaft, a rotatable collar upon said bearing, a track having a 40 fixed section supported from said rotatable collar, a vertically swinging section for the track pivoted at its ends to the ends of the stationary section, means carried by the 45 blades for engagement with said track, a vane carried by said rotatable collar for holding the blades to the wind, a vertically swinging arm for raising and lowering the 50 movable section of the track, said arm having its pivot carried by said collar, a ring vertically movable upon the bearing and disposed beneath the arm, a spring pressed pawl pivoted upon the arm and engaged with said 55 ring, and means for manually raising and lowering said ring.
4. In a windwheel, the combination of a vertical shaft, spokes radiating therefrom, feathering blades upon said spokes, a tubular bearing surrounding the shaft, a rotatable 60 collar upon said bearing, a track having a fixed section supported from said rotatable collar, a vertically swinging section for the track pivoted at its ends to the ends of the stationary section, means carried by the 65
- blades for engagement with said track, a vane carried by said rotatable collar for holding the blades to the wind, a vertically swinging arm for raising and lowering the movable section of the track, said arm having its pivot carried by said collar, a ring vertically movable upon the bearing and disposed beneath the arm, a spring pressed pawl pivoted upon the arm and engaged with said ring, and a cam lever for raising 70 and lowering said ring.
5. In a windwheel, the combination of a vertical shaft, spokes radiating therefrom, feathering blades upon said spokes, a tubular bearing surrounding the shaft, a rotatable 80 collar upon said bearing, a track having a fixed section supported from said rotatable collar, a vertically swinging section for the track pivoted at its ends to the ends of the stationary section, means carried by the 85 blades for engagement with said track, a vane carried by said rotatable collar for holding the blades to the wind, a vertically swinging arm for actuating said movable section of the track, said arm having its 90 pivot carried by the collar, a ring arranged for vertical movement on the bearing beneath said arm, means carried by the arm and engaged with said ring, a forked lever to straddle the bearing and pivotally mounted thereon, the free ends of the lever having cam portions to engage and actuate said ring, and an operating connection attached to the other end of the lever.
6. In a windwheel, the combination of a 100 vertical shaft, spokes radiating therefrom, feathering blades upon said spokes, a tubular bearing surrounding the shaft, a rotatable collar upon said bearing, a track having a 105 fixed section supported from said rotatable collar, a vertically swinging section for said track pivoted at its ends to the ends of the stationary section, means carried by the 110 blades for engagement with said track, a vane carried by said rotatable collar for holding the blades to the wind, a vertically swinging arm carried by the collar and adapted to actuate the movable section of the track, a ring vertically movable upon the bearing and provided with slotted 115 depending members arranged at diametrically opposite points, pivots projecting from the bearing and through the slots in said members to guide the ring in its sliding movement, a yoke-shaped lever pivoted upon said pivots and having its free ends formed with cam portions to engage and actuate the ring, a spring pressed dog or pawl carried by the 120 arm and adapted to engage said ring, and means for actuating said lever.
7. In a windwheel, the combination of a 125 supporting structure, feathering blades, a rotatable member carrying a track having a vertically swinging section, an arm for supporting said swinging track section, means

carried by the blades for engagement with
said track, a vertically slideable ring upon
the structure, a spring pressed pawl pivoted
to the arm and engaged with the ring and a
yoke-shaped lever pivoted to the structure
and having cam portions to engage and
actuate said ring.

In testimony whereof I hereunto affix my
signature in the presence of two witnesses.

DANIEL BENTON WOOD.
